UNITED STATES PATENT OFFICE.

WALTER H. COLES, OF TROY, OHIO.

NOZZLE.

1,104,965.

Specification of Letters Patent. Patented July 28, 1914.

Application filed November 17, 1913. Serial No. 801,336.

To all whom it may concern:

Be it known that I, WALTER H. COLES, a citizen of the United States, and a resident of the city of Troy, in the county of Miami and State of Ohio, have invented certain new and useful Improvements in Nozzles, of which the following is a full, clear, and exact description, reference being had to the accompanying drawings, forming part of this specification.

In the use of nozzles for making a very fine jet of liquid, and especially in overhead irrigating systems where a large number of tiny jets of water must be thrown from a long pipe, it is found that clogging is very likely to occur. It has been found that if a jet of, say, one-thirtysixth of an inch is to be thrown and if there is any surface against which the jet must play before it can get out of the nozzle, that then clogging is almost bound to result, no matter how high the pressure applied to the liquid. A long passage of needle size will not suffice, therefore, and neither will it do to allow the jet to play against any abutment in the nozzle. Then also the construction of the inlet end of the nozzle often results in clogging by allowing the liquid to enter the nozzle from a concave surface. This will allow that playing of the currents which will result in the accumulation of tiny particles sufficient to clog up the small inlet.

The object of this invention is to provide a nozzle which will throw a needle jet of any practical diameter, say as small as one-thirtysixth of an inch, and this without any tendency to clog.

It is further desired to get a clean stream or jet which is not deflected, and which is therefore especially useful in overhead irrigation work where a great number of jets are used and an even water distribution desired. This I accomplish by that certain construction and arrangement of parts to be hereinafter specifically pointed out and claimed, whereby all eddy currents and deflection and stoppages are eliminated.

In the drawings, Figure 1 is a section through a nozzle embodying my invention, mounted in a pipe, with another similar nozzle in elevation. Fig. 2 is an enlarged sectional view of a nozzle of modified form from the first. Fig. 3 is a plan view, taken with the mouth of the nozzle toward the observer. Fig. 4 is also a plan view of the same, from the inside.

The nozzles are shown here mounted in a pipe 1, by screwthreading their shanks 2 and screwing the same into properly prepared openings in the pipe. The mouth of the nozzle is formed with the outer walls flattened to make a nut 3 which facilitates insertion and removal of the nozzle. This structure above described forms no essential part of the improved nozzle here, but is merely the means of adapting it to its specially valuable use in an irrigating system. The pipe 1 is shown here as a two-inch pipe, and this is the size used in an irrigating system. The apertures 4, in the nozzles, which communicate directly with the interior of the pipe are preferably in such a system of one-thirtysixth of an inch in diameter. The aim is, in irrigation, to get the largest amount of water through the smallest hole, wherefore this nozzle is preferably adapted for this purpose.

The aperture or jet hole 4 is placed at the center of the convex inner end 5 of the nozzle. The thickness of this end is to be no greater than the diameter of the aperture, if this is possible. The convex form of the surface surrounding the jet hole prevents the lodging of particles of dirt partway across the inlet. It also prevents the slight eddying of currents which would take place in a concave form, which would also result in the lodging of particles of dirt. The thinness of the wall, and hence the extreme shortness of the passageway through which the jet of liquid must pass, prevents the formation of crusts in the passage, and insures the immediate ejecting from the nozzle of any particle of dirt which passes through the inlet. The nozzle is designed so that the jet of liquid 6, when it passes through the jet inlet 5, has no further contact with the nozzle even upon ordinary deflections. Two forms of barrel are shown, a bell shaped barrel 9, and a cone shaped barrel 8. Through each of these the jet will pass without dashing against the walls. The mouth 10 of the nozzle is in each case as wide as practical, having regard for strength of parts. This form of barrel and mouth removes possibility of clogging by encrusting or settling of particles of dirt and also projects the jet so as to permit it to maintain its jet form and not break into spray, for a greater distance than it could without protection from wind and particles carried by the wind.

It is now evident from the construction

and advantages detailed that my improved nozzle is effective and simple. Especially in the irrigating art it has done away with great disadvantages of the past.

5 Having thus described my invention, what I claim as new and desire to secure by Letters Patent, is:—

10 1. A nozzle having a minute jet inlet of substantially the same length and diameter, and a barrel of a flaring shape so that its wall is out of contact with the jet at ordinary deflections.

15 2. A nozzle having a minute jet inlet of substantially the same length and diameter, a barrel with walls flaring outwardly from the hole and a mouth at the end of the barrel of a diameter greater than the mean diameter of the barrel.

20 3. A nozzle having a small jet inlet, a concave inner end in the center of which the inlet is located, a barrel long and wide in comparison with the inlet and a mouth at the end of the barrel of a diameter greater than the mean diameter of the barrel.

25 4. A nozzle having a minute jet inlet of

substantially the same length and diameter, a concave inner end in the center of which the jet is located, a barrel long and wide in comparison with the inlet and a mouth at the end of the barrel of a diameter greater than 30 the mean diameter of the barrel.

5. In a nozzle, a means for forming a minute jet, means for protecting the entrance to said jet forming means, means for protecting the jet upon leaving said forming means, said protecting means having a long, flaring barrel so as to be out of contact with the jet in its normal direction. 35

6. In a nozzle, a means for forming a minute jet, said means being of substantially the same length and cross section, means for protecting the entrance to said jet forming means, means for protecting the jet upon leaving said forming means, said protecting means out of contact with the jet in 40 its normal and ordinary deflected direction. 45

WALTER H. COLES.
